(57) **CLAIM**

The ornamental design for an antenna base, as shown and described.

DESCRIPTION

FIG. 1 is a left elevational view of an antenna base showing our new design;

FIG. 2 is a front elevational view thereof;

FIG. 3 is a right elevational view thereof;

FIG. 4 is a bottom plan view thereof;

FIG. 5 is a top plan view thereof;

FIG. 6 is a rear elevational view thereof;

FIG. 7 is a perspective view thereof; and,

FIG. 8 is a perspective view thereof.

The broken lines in the drawings represent unclaimed portions of the design, which form no part of the claim.
